JACKET

Adolph Ostwald, Staten Island, N.Y.

Application February 27, 1958, Serial No. 49,826

Term of patent 14 years

(Cl. D3—4)

The figure is a side elevation of a jacket showing my new design, the opposite side being substantially identical therewith and the front and back of the jacket being conventional in appearance.

The essential features of my design reside in the braid trim on the sleeves as shown in full lines on the drawing.

I claim:

The ornamental design for a jacket, as shown and described.
